UNITED STATES PATENT OFFICE

102,043

DESIGN FOR A BOOT JACK

Marion O. Westbrook, Sonora, Tex.

Application June 6, 1936, Serial No. 63,082

Term of patent 3½ years

To all whom it may concern:

Be it known that Marion O. Westbrook, a citizen of the United States, residing at Sonora, in the county of Sutton and State of Texas, have invented a new, original, and ornamental Design for a Boot Jack, of which the following is a specification, reference being had to the accompanying drawing, forming part thereof.

Fig. 2 is a side elevation.

Fig. 3 is a front view.

I claim:

The ornamental design for a boot jack as shown.

MARION O. WESTBROOK.
